(57) **CLAIM**

The ornamental design for a light bar for cruiser emergency vehicles, as shown and described.

DESCRIPTION

FIG. 1 is a top, right perspective view of a light bar for cruiser emergency vehicles showing my new design;

FIG. 2 is a top view thereof;

FIG. 3 is a bottom view thereof;

FIG. 4 is a front view thereof;

FIG. 5 is a back view thereof;

FIG. 6 is a left view thereof;

FIG. 7 is a right view thereof; and,

FIG. 8 is a view of the light bar for cruiser emergency vehicles mounted on the roof of vehicle.

In the drawings, the broken line showing of mounting hardware depicts environmental subject matter and forms no part of the claim.
